(Cl. D88—1)

To all whom it may concern:

Be it known that I, Roy E. Lushbaugh, a citizen of the United States and resident of the city of New Albany, in the county of Floyd and State of Indiana, have invented a new, original, and ornamental Design for a Fair Leader or Similar Article, of which the following is a specification, reference being had to the accompanying drawings, forming a part thereof.

Fig. 2 is a front view of the same.

Fig. 3 is a rear view of the same.

Fig. 4 is a side view of the same.

The characteristic features of my design reside in the opposed disposition of a substantially L-shaped hook and a beveled end surface, both at the same end of a midwise constricted substan-

tially cylindrical body, all in combination as shown.

I claim:

The ornamental design for a fair leader or similar article, as shown and described.
